(57) **CLAIM**

The ornamental design for a connector, as shown and described.

DESCRIPTION

FIG. 1 is a perspective view taken from a top, front, right side of a connector, according to a first embodiment of my new design;

FIG. 2 is a front elevation view thereof;

FIG. 3 is a perspective view taken from a top, front, right side of a connector, according to a second embodiment of my new design; and,

FIG. 4 is a front elevation view thereof.

The dash dot lines immediately adjacent to the shaded areas in the views represent the boundaries of the claimed design. The dashed lines in the figures illustrate the portions of the design that form no part of the claimed design. None of the broken lines form any part of the claimed design.
